US00D795074S

(12) **United States Design Patent** (10) **Patent No.:** **US D795,074 S**
Staab (45) **Date of Patent:** **** Aug. 22, 2017**

(54) **COSMETIC CONTAINER**(71) Applicant: **Mary Kay Inc.**, Addison, TX (US)(72) Inventor: **Jenny DeMarco Staab**, Frisco, TX (US)(73) Assignee: **Mary Kay Inc.**, Addison, TX (US)(**) Term: **15 Years**(21) Appl. No.: **29/537,044**(22) Filed: **Aug. 21, 2015****Related U.S. Application Data**

(62) Division of application No. 29/511,912, filed on Dec. 15, 2014, now Pat. No. Des. 739,741, which is a division of application No. 29/458,540, filed on Jun. 20, 2013, now Pat. No. Des. 721,967.

(51) **LOC (10) Cl.** ..... **09-01**(52) **U.S. Cl.**USPC ..... **D9/504**; D9/454(58) **Field of Classification Search**
